VALVE MANIFOLD

Frank P. Roesch, Chicago, Ill., assignor to The Standard Stoker Company, Incorporated, a corporation of Delaware

Application August 10, 1938, Serial No. 224,104

4 Claims. (Cl. 277—50)

This invention relates to a valve manifold which consists of an integrally cast body, suitably cored to provide a plurality of passages each having a valve for controlling the flow of fluid therethrough. The invention is shown as applied to the fuel distributing jet of a stoker, although its use is not restricted to any particular installation.

It is an object of my invention to provide a simple and compact manifold that can be cast with a minimum of uneven shrinkage and that will not spring out of shape when the casting is cooled.

It is another object of the invention to provide a novel manifold that combines compactness with a maximum of strength and rigidity and that can be economically constructed.

Other objects and advantages of the invention will become apparent from the following description and the accompanying drawings.

Referring to the drawings:

Fig. 1 is a fragmentary view in central vertical section through a stoker embodying a pressure fluid distributing means, with certain portions of that stoker in elevation, and in which construction, the novel manifold is employed;

Fig. 2 is a sectional view on the line 2—2 of Fig. 1 with the manifold shown in elevation;

Fig. 3 is a sectional view of the manifold taken on the line 3—3 of Fig. 2;

Fig. 4 is a sectional view taken on the line 4—4 of Fig. 3;

Fig. 5 is a sectional view taken on the irregular line 5—5 of Fig. 4; and

Fig. 6 is a sectional view taken on the line 6—6 of Fig. 4.

Referring particularly to Figs. 1 and 2 of the drawings, a stoker discharge conduit is shown at 10, communicating with an opening 11 in the wall 12 of a furnace 13, such as that of a locomotive boiler. The discharge conduit 10 delivers fuel onto a distributing plate 14 disposed in the opening 11 and from which plate the fuel is projected into the furnace to the various parts of the firebed by blasts of fluid under pressure issuing from the pressure fluid jet member 15.

The jet member 15 is provided with a plurality of separated chambers, such as 16, 17, 18, 19 and 20, arranged to receive fluid under pressure from a suitable source of supply through the pipes 16a, 17a, 18a, 19a and 20a, respectively. The blasts of pressure fluid for projecting fuel from the plate 14 issue from the jet openings 21 of the jet member 15, a plurality of such jet openings, prefer-

ably, communicating with each of the chambers 16, 17, 18, 19 and 20.

The streams of pressure fluid issuing from the jet openings of the several chambers are directed toward predetermined areas of the firebed, and in order to provide for adequate control of the intensity of these blasts for effecting proper control of fuel distribution, delivery of pressure fluid to the pipes 16a, 17a, 18a, 19a and 20a is controlled by valves, designated respectively as 16b, 17b, 18b, 19b and 20b, each of which is manually controlled and carried by the manifold M. The manifold M receives pressure fluid from a suitable source of supply, such as the boiler of the locomotive, through the main lead 22. Within the body portion 23 of the manifold M, there is provided a chamber 24 receiving pressure fluid from the main lead 22. The pressure fluid passes from the chamber 24 into a cored triangular-shaped endless passage 25 formed in the manifold body 23 through an opening 26 which is manually controlled by the main valve 27 carried by the manifold.

The pipes 16a, 17a, 18a, 19a and 20a are screwed into the manifold M and communicate with the passage 25 through the respective secondary passages 16c, 17c, 18c, 19c and 20c therein. The passages 16c, 17c, 18c, 19c and 20c are separated from the main passage 25 by the partition 16d, 17d, 18d, 19d and 20d, respectively, and pressure fluid passes from the main passage 25 to the secondary passages through the openings 16e, 17e, 18e, 19e and 20e, in the partitions 16d, 17d, 18d, 19d and 20d, respectively, the size of the openings being manually controlled by the valves 16b, 17b, 18b, 19b and 20b, respectively. The manifold M is secured to the locomotive backhead 12 by suitable means, such as the threaded bolts 40 passing through the web 41 and bosses 42 formed with the body portion 23 of the manifold.

Each of the valves, including the main valve 27, comprises a stem 28 threaded into a bonnet 29, the stem having a valve member 30 at its inner end and the valve handle 31 at its outer end. A valve seat 32 is threaded into the body portion of the manifold between the passage 25 and each of the passages 16c, 17c, 18c, 19c and 20c, and between the chamber 24 and passage 25. Thus, pressure fluid will pass into the passage 25 and the passages 16c, 17c, 18c, 19c and 20c at various pressures determined by the setting of the valves.

The manifold embodying an endless main passage 25 is extremely compact and can be secured to the locomotive backhead without inconvenience.

or interference with other equipment. The construction of the manifold insures against uneven shrinkage and undesired springing or warping out of shape when the manifold is cast and cooled.

5. I claim:

1. A valve body member having formed therein an endless main passage, said body member having a pressure fluid intake opening formed to receive a valve seat communicating with said main passage, said body member having a plurality of secondary passages, partitions within said body member separating said secondary passages from each other, a partition separating said main passage from said secondary passages, said last-named partition being provided with a plurality of ports, each port being formed to receive a valve seat and providing communication between said main passage and one of said secondary passages, said body member being provided with a plurality of discharge openings, each of said discharge openings communicating with one of said secondary passages.
2. A valve body member having therein a triangular main passage, said body member having a fluid pressure admission port between the ends of one of the legs of said triangle formed to receive a valve seat, a plurality of secondary passages formed in said body member at spaced intervals, said body member being provided with a plurality of fluid emission ports, each emission port communicating with one of said secondary passages and means forming an opening between each of said secondary passages and said main passage providing communication therebetween, said opening formed to receive a valve seat.
3. A valve body member having a chamber formed therein and a pressure fluid intake opening communicating with said chamber, said body member having an endless main passage formed therein, a partition in said body member sepa-

rating said chamber from said main passage, said partition having a port providing communication between said chamber and said main passage, said port being formed to receive a valve seat, said body member having a plurality of secondary passages, partitions within said body member separating said secondary passages from each other, a partition separating said main passage from said secondary passages, said last-named partition being provided with a plurality of ports, each port being formed to receive a valve seat providing communication between said main passage and one of said secondary passages, said body member being provided with a plurality of discharge openings, each of said discharge openings communicating with one of said secondary passages.

4. A triangular shaped valve body member having formed therein a triangular-shaped main passage, a plurality of secondary passages, partitions within said body member separating said secondary passages from each other, a partition separating said main passage from said secondary passages, said last-named partition being provided with a plurality of ports, each port being formed to receive a valve seat providing communication between said main passage and one of said secondary passages, said triangular shaped body member having a pressure fluid intake opening in one leg thereof between the ends of said leg and communicating with said main passage, said last named opening being formed to receive a valve seat, and means providing a plurality of pressure fluid discharge openings, each of said discharge openings communicating with one of said secondary passages and opening through the other two legs of said triangular shaped body member.

FRANK P. ROESCH.
